CAN OPENING KEY

William I. Colvin, Saratoga, Calif., assignor to
 Pacific Can Company, San Francisco, Calif., a
 corporation of Nevada

Application November 20, 1950, Serial No. 196,621

2 Claims. (Cl. 220—52)

1

This invention relates to new and useful improvements in can opening key and method of forming same. More particularly, the invention relates to a can-opening key adapted to be welded onto a can end or some other accessible location on a tear strip can, said key being so attached that it may be disconnected manually with a minimum of effort and then employed to wind the tear strip of the can body and thus open the can.

Conventional can-opening keys are formed of a wire shank bent at one end to form a handle and provided at the opposite end with a rectangular slot for the reception of the protruding tongue of the tear strip, with means for welding or otherwise attaching the key to the can during transportation and storage prior to opening, and with means for weakening the key between the tear strip slot and the point of attachment so that the consumer may disconnect the key from the can immediately prior to opening the can.

The improvement of the present invention resides in novel structure providing means for attaching the key to the can and weakening the key for disconnection. The invention further relates to a method of forming a key of such character.

With the above and other objects, features and advantages in view, the invention consists in the matters hereinafter set forth and more particularly pointed out in the appended claims, reference being had therein to the accompanying drawings, in which:

Fig. 1 is a top plan of a key made in accordance with the present invention;

Fig. 2 is a side elevation of the key shown as attached to a can end as the key is being raised to sever the key from said can end;

Fig. 3 is a plan of the die block used in forming said key;

Fig. 4 is a vertical section taken substantially along the line 4—4 of Fig. 3;

Fig. 5 is a bottom plan of a punch used with said die block; and

Fig. 6 is a section taken substantially along the line 6—6 of Fig. 5.

As illustrated in the accompanying drawings, a key 10 is provided for attachment to a can end 11, preferably by welding. Such a key comprises a shank 12 formed of round wire, a handle 13 integrally formed by bending the wire in a rectangular shape, and an elongated, flattened tail 14 at the end opposite said handle. Tail portion 14 is provided with a rectangular slot 16 through which fits the tongue of the tear strip of the can, as is well understood in this art. In order to

provide means for weakening the shank a hole 17, which may be circular or some other convenient shape, is punched in the tail portion 14 between slot 16 and the extremity of the tail. 5 Sufficient stock remains between the circumference of hole 17 and the side edges 22 of the tail so that the key will remain on the can during handling prior to the time that the consumer desires to open the can, but the removal of 10 material by punching of hole 17 weakens the key adjacent the hole so that the key may be readily severed by fracture adjacent the hole when desired.

In order to facilitate welding of key 10 to can end 11, it is desirable to provide one or more protuberances 21 projecting from the flattened tail 14 of the key. Said protuberances 21 perform several functions. One function is that upon application of pressure on the key against

15 the can during welding the protuberances penetrate lacquer or other dielectric material on the can end surface which might otherwise interfere with passage of welding current until said protuberances establish metal-to-metal contact with 20 the can end. Another function of the protuberances is the localization of the passage of welding current in that contact is established through said protuberances and current passes therethrough rather than through some other portion 25 of the key; thus the location of the weld may be accurately controlled.

In accordance with the present invention, two welding protuberances 21 are located in flattened portion 14 between hole 17 and the edges 22 of 30 the shank by depressing the material on either side of hole 17 in a transverse bight 23. Thus the material forming protuberances 21 is pressed downward so as to depend from the lower flattened surface 14 of the shank and when the key 35 is brought into contact with can end 11, and pressure applied above the area in which the protuberances are located, the protuberances, rather than any other portion of the key, are forced into contact with the can end.

40 It will be noted that hole 17 and bight 23 are located spaced from the end of the key so that when the consumer lifts handle 13 in order to disconnect the key from the can (see Fig. 2), the extreme anterior portion 24 engages the surface 45 of can end 11 and becomes a fulcrum for the leverage required to fracture the material.

The formation of shank portion 14 is accomplished in a single stamping operation of a press. It will be assumed that key 10 has been formed 50 with handle 13 at one end. Handle 13 thus pro-

vides a means for locating the key with respect to the die 31 by reason of the location of a raised boss 32 on the die which is also rectangular and which fits snugly within the rectangular hole in handle 13. Die block 31 and punch 33 are formed with projecting portions 34 and 36 respectively which flatten shank 12 to form flattened portion 14 by pressing the round wire of shank 12 therebetween. Depressed bight 23 is formed by transversely extending rib 37 in punch 33 and a corresponding hollow 38 in die 31. Punch 33 is made with a double-acting portion 40 which carries male portions 39 and 41 which simultaneously punch out slot 16 and hole 17 by coaction with openings 42 and 43 in die 31 10 after the shank has been flattened. Flattening of shank 12, depression of bight 23 and punching of slot 16 and hole 17 are all accomplished in a single stroke of the press.

After formation of handle 13, punch 33 contacts shank 12 and presses the same against die 31 between projection portions 34 and 36 thereby flattening said shank and forming the depressed bight 23. Thereafter by means well understood in the punch art, secondary portion 38 of punch 33 is actuated to punch out slot 16 and hole 17, respectively.

It will be understood that whereas a preferred embodiment of the invention has been described and illustrated, changes may be made therein 30 without departing from the spirit of the invention and the scope of the appended claims.

What is claimed is:

1. In a can opening key of the type adapted to be welded to a portion of a can and subsequently severed therefrom immediately prior to usage, said key having a handle and a shank, the improvement comprising an elongated, flattened tail portion on the end of said shank remote from said handle, said tail portion being 40 apertured for reception of a tear strip tongue

and also separately centrally apertured between the tear strip aperture and the end of said tail portion at a location spaced inwardly from the extremity of said tail, said tail portion being depressed in a pair of transverse bights at either side of said last-mentioned aperture between said last-mentioned aperture and the side edges of said shank, and a pair of welding protuberances depending from the bottom surface of said tail portion and formed by depressing said bights.

2. A can-opening key formed of round wire into a handle portion and a shank, said shank being flattened approximately the last two-thirds of its length and apertured in a rectangular slot in said flattened portion and provided with a second aperture in said flattened portion substantially midway between said rectangular slot and the end of said key, said flattened portion being depressed in a bight at said second aperture transverse to said shank, and a pair of welding protuberances formed of the material between said second aperture and the side edges of said flattened portion, said protuberances being depressed below the bottom surface of said flattened portion, said key being structurally weakened along said bight by removal of material at said second aperture and depression of said bight.

WILLIAM I. COLVIN.
